UNITED STATES PATENT OFFICE

**ROTARY AXIAL
VALVE**
David Lewis Ball,
Application October
1962 **3 Claims.**

This invention relates to rotary compressors, pumps and motors.

Its principal object is to provide a rotary compressor, pump and motor which has a relatively higher volumetric capacity than have conventional rotary machines of the same general type and size.

Another object is the provision of a rotary compressor, pump and motor which is capable of efficient operation at a higher rate of speed than is the case with conventional machines of the same type.

A further object is to provide a rotary compressor, pump and motor whose stator alone carries the eccentric or cam surfaces which engage the vanes, the rotor being concentrically uniform in all respects.

Still another object is the provision of a rotary compressor, pump and motor whose rotor comprises, and serves the function of, a flywheel.

A still further object is the provision of a rotary compressor, pump and motor whose vanes are actuated solely by means of the cam surfaces by which they are engaged.

Another object still is to provide a rotary compressor, pump and motor in which the removal of shims compensates for the wear of the moving parts.

These and other objects are attained by mechanism illustrated in the accompanying drawing in which

Figure 1 is a vertical, longitudinal section of the entire device;

Figure 2 is a horizontal section thereof on the line 2-2 of Figure 1;

Figure 3 is a vertical, transverse section thereof on the line 3-3 of Figure 1; Figure 4 is a perspective view of one of the cam plates or rings which engage the vanes shown together with the end plate of the housing to which it is affixed; Figure 6 is a plan view of the rotor mounted

on the rotor shaft, showing the vanes carried by the rotor.

The device herein disclosed and claimed may be used as a compressor, as a pump or as a motor. In each case the mechanism would be the same. Since this is the case, for the sake of convenience, the device will hereinafter be referred to as a compressor and described as such.

Essentially the device consists of a rotor 10 and a stator 30. The rotor comprises a vane-carrying wheel 11 which is integral with a drum

BOTARY AXIAL VANE COMPRESSOR

pplication October 5, 1944, Serial No. 557,248

(Cl. 230—152)

2

12, the wheel being coaxial with the drum and mounted centrally thereof. The two are uniformly proportioned in all respects, their outer peripheral surfaces being, respectively, equidistant at all points from their common axis. The two sides of the wheel are perfectly flat and perfectly parallel to each other and situated at right angles to the peripheral surface. A plurality of uniformly spaced radial slots 13 is formed in the wheel to receive an equal number of vanes 14. There is close tolerance yet slidable clearance between the sides of the vanes and those of the slots.

Each vane 14 comprises three elements which are doweled and screwed together; an outer horizontal member 15 having a convex upper surface, an inner horizontal member 16 having a concave lower face, and a removable shim member 17 which is situated between the lower face of the outer member and the upper face of the inner member. Dowel pins 18 and countersunk screws 19 join the three members and hold them in line. The complete vane comprises a unit which has four perfectly flat sides, the adjacent of said sides being at right angles to each other, the opposite of said sides being parallel to each other. The upper (convex) surface is concentric with the lower (concave) surface.

30 The drum of the rotor is fixedly mounted on a sleeve 20 which in turn is fixedly mounted on a rotor shaft 21. The rotor shaft is carried by a pair of adjustable bearings 22 which are affixed to a base member 23. Since the device is now being considered as a compressor, the rotor shaft is connected to an electric motor or to any other suitable source of motive power (not shown) by means of a pulley belt (not shown) which engages the pulley 24 shown mounted on the rotor shaft.

50 The stator 30 comprises a pair of cam plates 31 which flank the wheel 11 of the rotor, a pressure ring 32 which encircles the wheel 11 in concentric relation thereto, a pair of side plates 33 which are mounted on the drum 12 of the rotor and are affixed to the pressure ring 32 and to the base 23, and inlet and outlet ports 34 and 35 respectively. Removable shims 36 are inserted between the side plates on the one hand and the pressure ring and base on the other. 55 Packing rings 37 are inserted between the side plates and the rotor drum to prevent leakage of the fluid but to permit of rotary movement of the drum relative to the side plates. The pressure ring, the base and the side plates comprise 60 the housing of the stator.

The cam plates comprise a pair of parallel plates which are affixed by means of welding or any other conventional means to the inner, facing walls of the side plates in diagonal or canted position relative thereto. When in such canted position, the outer and inner peripheries of said cam plates lie in concentric relation with respect to the pressure ring and the drum of the rotor, the fit between the cam plates and the pressure ring being tight and the fit between the cam plates and the drum being snug, but permitting of rotary movement of the drum relative to the cam plates.

The inner faces of the canted cam plates are formed of an infinite number of radial lines, each of which bears at right angles to the outer peripheral surface of the drum and the inner peripheral surface of the pressure ring. All corresponding radial lines of the two cam plates lie in parallel relationship to each other and to the corresponding sides of vanes 14 which the cam plates engage. The distance between said cam plates at all points is equal to the width of the vanes. The length of each said radial line is equal to the height of the vanes. The cam plates are so situated relative to the rotor wheel 11 that the latter is in slidable contact with the former at two diametrically opposite points.

Flanking these contact points are inlet and outlet ports 34 and 35 respectively. These may be seen clearly in Figure 4. An inlet pipe 38 is connected to each inlet port and an outlet pipe 39 is connected to each outlet port.

The shims perform a very useful function. Shim member 17, for example, may be inserted to increase the height of vane 14 by way of compensation for wear either of the curved surfaces of the vane, or of the outer peripheral surface of the drum or of the inner peripheral surface of the pressure ring or of all of said surfaces combined. Shims 36 may be removed to shorten the distance separating the two cam plates in order to compensate for wear of the inner faces of said plates or of the side surfaces of the vanes which said plates engage, or of said faces and side surfaces combined.

The device functions in the following manner: The electric motor or other source of motive power causes the rotor shaft and hence the rotor to rotate. The vanes which the rotor carries, move together with the rotor, being prevented from leaving the slots by the pressure ring and the cam plates. In addition, the vanes are caused to move from side to side in response to the passive action of the cam plates. In consequence of such movement, partial vacuums are created behind the moving vanes and compression areas are set up in front of them. The effect is to suck fluids into the space or chamber behind the moving vanes through the inlet ports, and to force the fluids out of the space or chamber in front of the moving vanes through the outlet ports. It will be seen that the construc-

tion of the rotor provides it with an additional function, that of a flywheel. It will be seen further that the sole actuating force of the vanes is provided by the engagement therewith of the cam plates.

The embodiment of the invention herein described is only one preferred form thereof. Modifications may be incorporated therein without departing from the principles thereof. For example, instead of the three vanes shown in the drawing, two or four or any other number may be used. Also the cam plates may be differently formed and disposed as long as the described cam surfaces are incorporated therein.

I claim:

1. In a machine of the character described, a vane comprising an outer member having a convex top edge, an inner member having a concave bottom edge, a shim positioned between the two members, and means holding said members and said shim together.

2. A vane for a fluid motor or compressor comprising an outer member having a convex top edge, an inner member having a concave bottom edge and a shim member situated between the bottom edge of the outer member and the top edge of the inner member, said members being detachably fastened together by means of screws.

3. A fluid motor or compressor comprising a rotor and stator, radial slots formed in said rotor and vanes slidably disposed in said slots, each of said vanes comprising an outer member having a convex pressure ring engaging surface, an inner member having a concave rotor engaging surface, a shim positioned between said outer and inner members and means for fastening said outer and inner members and said shim together, said stator consisting of an imperforate pressure ring which encircles the rotor and which engages the outer edge of the vanes, side plates connected to said pressure ring and a pair of cam plates fastened to the inside of said side plates, said cam plates being mounted in canted position relative to the axis of the rotor, said cam plates having parallel vane engaging faces which bear at right angles to said axis and said cam plates being provided with inlet and outlet ports.
